Patented Sept. 5, 1916.

UNITED STATES PATENT OFFICE.

THOMAS F. LEAHEY, OF POUGHKEEPSIE, NEW YORK.

CONNECTOR FOR ELECTRICAL CONDUCTORS.

1,196,792.

Specification of Letters Patent.

Patented Sept. 5, 1916.

Application filed October 11, 1915. Serial No. 55,179.

To all whom it may concern:

Be it known that I, THOMAS F. LEAHEY, a citizen of the United States, and a resident of the city of Poughkeepsie, in the county 5 of Dutchess and State of New York, have invented certain new and useful Improvements in Connectors for Electrical Conductors; and I do hereby declare the following to be a full, clear, and exact description of 10 the invention, such as will enable others skilled in the art to which it appertains to make and use the same.

This invention relates to connectors for electrical conductors and more particularly 15 to that class of connectors used in line construction for connecting the wires of the line in a continuous circuit.

One object of my invention is to provide 20 a connector in which the assembling of the connector in the line effects a direct electrical and physical connection between the wires themselves without the interposition of any part of the connector in the circuit.

A further object of the invention is to provide 25 a connector of this class which may be made throughout of fiber or other insulating material and which is designed to be of such light weight as to produce no sagging of the stretch of the wire containing the connector and yet of sufficient strength and 30 rigidity to withstand all strains to which it may be subjected in assembling or as part of the line.

A further object of my invention is to provide 35 a connector of this type in which the ends of the wires are twisted together by relative rotation of the parts of the connector without mutilating the wires in any way as by cutting or indenting or by overstraining 40 in twisting, and in which the wires are maintained in intimate electrical contact throughout the entire length of their overlapped portions, thus reducing the resistance 45 of the connection to a minimum.

A further object of the invention is to provide 50 a connector especially designed for joining insulated wires in such manner that the connector overlaps the covering of the wires and of itself preserves the continuity 55 of the insulation, thereby obviating the usual necessity of winding or otherwise insulating the joint after the connection is made.

With the above objects in view, my invention 55 consists in the construction hereinafter described and illustrated in the accompanying drawings, in which,

Figure 1 is a longitudinal section through one form of connector embodying my invention showing it assembled in the line after the connection has been made. Fig. 2 is a 60 longitudinal section through the connector shown in Fig. 1, but at right angles thereto. Fig. 3 is a transverse section on line 3—3 of Fig. 2. Fig. 4 is a longitudinal section of a modified form of connector embodying a construction especially adapted for use with insulated wires on a plane corresponding to the plane of Fig. 1. Fig. 5 is a longitudinal section through the connector shown in Fig. 4 but at right angles thereto, and Fig. 6 is a 70 transverse section on line 6—6 of Fig. 4. Fig. 7 is a sectional view of a further modification.

Referring now to the drawings and particularly to Figs. 1, 2 and 3, the numerals 7 75 and 8 indicate the two parts of the connector whose relative rotation effects the twisting together of the overlapped ends of the two wires 14 and 15. Each part of the connector is preferably made of indurated fiber 80 or similar insulating material and each comprise a flattened outer portion having a substantially elliptical bore for receiving the wires in parallelism and holding them against rotation one around the other, the 85 wires fitting snugly in the bore so that they are frictionally held against longitudinal movement in the bore and their adjacent faces are pressed together in close electrical contact. The adjacent portions of the parts 90 7 and 8 are each enlarged to a circular cross section and are provided with complementary threads 9 and 10, respectively, whereby a limited relative rotation will securely join the parts together. The circular portion of 95 one of the parts, 8 for example, is long enough to provide a chamber 11 to accommodate the desired length of the twisted together portion of the wires, preferably three or four turns.

In assembling the connector, the two parts thereof with their joint unscrewed, are slipped over the end of one wire and the end of the other wire thrust in from the opposite direction to give the desired lap. 105 The two parts are then screwed together, the flattened portions providing a suitable grip for the fingers or wrenches if the wires are stiff. The relative rotation of the two parts twists the wires together as will be 110 obvious; the resistance of the wires to movement in the bores 12 as they are drawn to-

gether by the twisting action producing a close twist even though the wires are so flexible as to offer little resistance to coiling.

It will be observed that the connector is entirely free throughout its length of shoulders or sharp corners of any kind which might cut or indent the wires, the bores 12 being gradually enlarged into circular cross section as indicated at 13. Also by holding the wires in close contact while twisting a tight twist is produced without producing abrupt turns in the wires which might weaken or break them.

In the modification shown in Figs. 4, 5 and 6, the connector is designed to produce a double twist in the connected wires. To this end the connector comprises three relatively rotatable parts, 16, 17 and 18 provided with complementary threads, whereby they may be connected together in axial alinement. The middle part 17 is interiorly of circular cross section at its threaded ends but is gradually reduced at its middle to provide an elliptical bore 19 corresponding in function with the bores 12 of the first described connector. The end portions 16 and 18 have their circular portions at the ends threaded for connection to the part 17, the chambers thus formed for receiving the twisted wires being gradually reduced to elliptical cross section for holding the wires beyond the twisted portions. The design of this connector as shown in the drawings is specially adapted for joining insulated wires, for which purpose the ends of the elliptical bores in the parts 16 and 18 are each closed at one side to prevent projection of the free ends of the bare wires as indicated at 20. Also the outer face of the connector is cylindrical throughout and is threaded at each end as shown at 21 to receive the sleeves 22 for inclosing the ends of the insulating covering 23 of the wires. The shortening of the wires produced by the twisting will draw the covering into the sleeves insuring a proper insulation of the joint.

In Fig. 7 I have illustrated an adaptation of my invention to flexible connectors embodying a hinged joint. In this connector the two parts 30, 31 which are hinged together on the bolt or rivet 32 are necessarily made of metal, as they must carry the current through the joint. I preferably form these parts of annealed tubing which is circular at its outer end and provided with an external thread 33. Immediately beyond the thread each tube section is flattened into an elliptical form to receive the ends of the parallel wires 34, 35, each piece 35 being a short length permanently fastened in the metal tube section of the connector by brazing or otherwise. Beyond the elliptical portion of the tube section 31 the tube is completely flattened to form the inner mem-

of the joint, while the tube section 30 is slit at its narrower edges and sufficiently flattened for its two sides to embrace the end of the section 31 forming therewith a hinged joint having large contact areas between the surfaces of the two parts thereby providing a good electric connection. The outer portions 36 of the two parts of the connector are preferably formed of insulating fiber and are similar in every respect to the corresponding sections of the connector illustrated in Fig. 1. In assembling the connector in the line, the line-wires 34 are thrust into the elliptical ends of the sections 36 while the joints between the sections are unscrewed and into the flattened portions of the metal tube sections in parallelism with wires 35. The joints are then screwed up and the connection formed just as in the straight line connectors previously described.

In the above described construction the greater portion of the connector may be made of fiber thereby greatly reducing the weight of the connector and also leaving a much shorter portion to be insulated by tape or otherwise in case the connector is used in an insulated line. In other respects this connector has all the advantages of the straight line connector.

I have shown the several parts of the connector as threaded together, but such threads are not altogether essential. The parts may instead be connected by a joint of smooth bore to maintain the alinement for none of the strain of the line is borne by the connector. The threads, if employed, may be of sufficient length to give the desired number of turns to the twist or may be of greater length, in which case the parts will be partially assembled before the wires are thrust in.

While the invention has been shown and described in all its preferred details, it is of course to be understood that the invention is not limited to such details except in so far as defined by the appended claims.

What I claim is:

1. A connector for electrical conductors comprising two tubular members each formed throughout of insulating material detachably connected for relative rotation, each of said members having a portion shaped to hold a corresponding length of both conductors in parallelism and against relative movement whereby relative rotation of said members will cause said conductors to be twisted together.

2. A connector for electrical conductors comprising a pair of tubular members each formed throughout of insulating material and having complementary parts maintaining said members in axial alinement and permitting their relative rotation, each of said tubular members having a portion of its

- bore shaped to hold said conductors in parallelism in intimate electrical contact and against rotation one around the other, whereby relative rotation of said members will cause said conductors to be twisted together.
3. A connector for electrical conductors, comprising a pair of tubular members having complementary parts maintaining said members in axial alinement and permitting their relative rotation, each of said tubular members having a portion of its bore substantially elliptical to hold said conductors in parallelism in intimate electrical contact and against rotation one around the other and one of said members having its bore enlarged intermediate the conductor gripping portions, whereby relative rotation of said members will cause said conductors to be twisted together in said enlarged portion.
4. A connector for electrical conductors comprising a pair of tubular members threaded together in axial alinement, said members having their bores at their adjacent ends of circular cross section with said bores beyond the circular portions gradually reduced to substantially elliptical cross section adapted to hold said conductors in parallelism and against rotation one around the other whereby relative rotation of said mem-
- bers will cause said conductors to be twisted together in said enlarged portion.
5. A connector for insulated electrical conductors comprising a plurality of tubular members of insulating material connected in axial alinement for relative rotation, said connectors having an intermediate portion of their continuous bore of circular cross section and end portions of substantially elliptical cross section to hold the conductors in contact and against rotation one around the other, said elliptical bore having one-half thereof closed at each end to cover the free end of the conductor.
6. A connector for insulated electrical conductors comprising a plurality of tubular members of insulating material connected in axial alinement for relative rotation, said connectors having an intermediate portion of their continuous bore of circular cross section and end portions of substantially elliptical cross section to hold the conductors in contact and against rotation one around the other, said members having flanges extending axially of their outer ends for receiving the ends of the insulated coverings of said conductors.

In testimony whereof I affix my signature.

THOMAS F. LEAHEY.
